MACHINE FOR OPERATING ON COUNTERS

Charles C. Gillis, Lynn, Mass., assignor to Gillis Counter Co. Incorporated, Lynn, Mass., a corporation of Massachusetts

Application July 16, 1937, Serial No. 154,032

14 Claims. (Cl. 12—63)

The present invention relates to the manufacture of counters and in one aspect consists in a novel machine for skiving and slashing counter blanks preparatory to molding them. In another aspect it consists in an automatically operating slashing mechanism which may be employed as an independent unit or as an attachment or auxiliary mechanism for a skiving machine.

In making certain types of shoes, of which 10 stitch downs are one example, the shoe manufacturers require counters having outwardly directed flanges as distinguished from the inturned flanges which are found in counters intended for shoes of other types. In preparing a counter 15 blank for molding an outturned flanged therein it has been the practice to slash a portion of the lower margin since this must be elongated in the molding operation. The slashes permit sections of the margin to fan out and lie flat without distortion of the upstanding walls of the counter thus facilitating the molding operation and improving the molded counter.

Prior to my invention counters have been 20 slashed as a distinct operation either by hand or by the aid of a slashing machine to which the counter blanks have been presented successively by an operator. An object of the present invention is to provide an automatically acting slashing machine to which counter blanks may be fed 25 mechanically from a magazine or other source of supply and by which the slashing operation is effected automatically, accurately and at high speed, without making any considerable demands upon the skill and judgment of an operator. To 30 this end an important feature of the invention consists in automatic blank feeding mechanism in combination with a rotary blade carrier and a cooperating presser or anvil roll, the feeding mechanism being organized to present successive 35 blanks in properly timed and accurately gauged relation to the blade carrier and the latter being constructed to slit or slash the margin of the blank so presented.

As herein shown and in accordance with another feature of the invention, provision may be made for relative adjustment of the slashing mechanism with respect to the feeding path of the counter blank, and the position or extent of the individual slashing cuts in the margin of 40 the counter may thus be regulated and controlled in accordance with the requirements of the work in hand.

I have discovered that the slashing mechanism of my invention may be advantageously associated with the skiving mechanism which is com-

monly used to reduce or bevel the marginal portions of the counter blank. Accordingly I contemplate taking the skived counter blank, as it passes accurately located from the skiving mechanism, and performing the slashing operation thereon while the blank is thus located. From this standpoint my invention consists in skiving mechanism of the roller or matrix type for reducing the margin of a counter blank, in combination with slashing mechanism so located and arranged as to slash the reduced margin of the blank in an area determined by the position previously imparted to the blank by the skiving mechanism.

While the design of the skiving mechanism is of secondary importance, and many different types are satisfactory, I have herein shown as a further feature of my invention a novel slashing mechanism comprising a rotary blade carrier having a series of parallel axially arranged blades, in combination with a cooperating presser roll of softer metal. The counter blank is passed between the cooperating members and the area slashed may be covered by regulating the setting of the two with reference to the position of the counter blank passing between them.

These and other features of the invention will be best understood and appreciated from the following description of a preferred embodiment thereof selected for purposes of illustration and shown in the accompanying drawings in which,

Fig. 1 is a cross-sectional view on the line 1—1 of Fig. 4.

Fig. 2 is a view in longitudinal section of the main shaft and associated parts.

Fig. 3 is a view in perspective of a counter which has been operated upon by the illustrated machine.

Fig. 4 is a rear view of the machine.

Fig. 5 is a view of the machine in end elevation, and

Fig. 6 is a view in perspective of the slashing roll.

As herein shown the slashing mechanism is incorporated in a counter skiving machine of commercial construction and only so much of that machine is shown as is necessary for an understanding of the present invention.

Journalized in the main frame 10 is a pair of transverse shafts 11 and 13 which carry respectively on their right hand ends, as seen in Fig. 4, the gear wheels 26 and 27 which intermesh and cause equal and opposite rotation of the two shafts. The lower shaft 11 carries a feed roll 12 and the upper roll 14 is formed with a matrix

cavity into which the central portion of the counter blank is forced as it is advanced to the splitting knife 17 which is mounted directly behind the bite of the two rolls in a support 16. Upon the entering side of the rolls 12 and 14 is provided a work table 15 from which successive counter blanks are delivered to the rolls by a reciprocating feed slide 18. The mechanism for operating the feed slide is not herein shown since it forms no part of the present invention.

The matrix roll mechanism is designed to bevel more or less of the marginal portion of the counter blank. For example, in Fig. 3 is shown a counter blank of the rocker bottom type which is one kind of counter that may be handled advantageously in the illustrated machine. It derives its name from the fact that its lower marginal edge is not straight, but is formed by two lines which diverge from a central point so that the flange of the molded counter tapers in a pronounced manner toward both forward corners.

In skiving such a counter blank it is customary to bevel the entire margin leaving a central portion 90 of full thickness and providing an upper curved and bevelled margin 91 and a lower bevelled margin 92 bounded by straight diverging edges. The matrix mechanism above described may be designed to bevel a counter blank in the manner suggested in Fig. 3 or in any other similar manner. In any case the counter blanks are pushed one at a time into the bite of the skiving rolls by the advancing movement of the feed slide 18, the blanks being positioned by suitable gauges, one of which 42 is shown in Fig. 1.

The main driving shaft 20 is journaled in bearings provided in the frame 10 directly behind the shaft 11. It is provided at its left hand end, as shown in Figs. 2 and 4 with a driving pulley 21. Its right hand portion is surrounded by a longitudinally movable tubular shaft 22 spaced from the shaft 20 by suitable bushings 19 and arranged to be driven independently of the shaft 20 and in the opposite direction as will presently appear. Keyed to the shaft 20 next to the pulley 21 is a pinion 24 and this pinion is arranged to mesh with a large pinion 25 fast on the left hand end of the roll shaft 11. The roll shaft is geared to the matrix roll shaft at its right hand end by the pinions 26 and 27 already mentioned and the pinion 27 of the lower shaft 11 meshes with an elongated pinion 28 journaled on a stub shaft 29 which projects from the right hand side of the machine frame 10, as shown in Fig. 4.

The slashing mechanism will now be described. This includes a presser or anvil roll 30, shown in Fig. 2 as secured to the tubular shaft 22 by set screws and having a brass ring section 31 set into its left hand end. Cooperating with the anvil roll 30 is a cutter roll or blade carrier 32 having a peripheral series of straight slashing blades 33 arranged upon a section of its left hand end corresponding in width to the brass section 31 of the anvil roll. The cutter roll 32 is fast upon a transverse shaft 34 journaled in a frame 35 which has a pair of hubs 36 journaled upon the tubular shaft 22 so that the whole frame 35 may be swung from an operative position shown in full lines in Figs. 1, 4 and 5 to an inoperative position shown in dot and dash lines in Fig. 1. The frame 35 is provided with an upstanding slotted ear 37 and may be detachably and adjustably secured to the main frame 10 of the machine by a clamping bolt 38 passing through the ear. It will be understood that the swinging frame 35, all the parts carried thereby, and the

tubular shaft 22 may be adjusted longitudinally upon the main shaft 20 so as to bring the slashing knives 33 transversely into any desired operating zone. The effective adjustment of the operating knives is thus in a direction at right angles to the major axis of the counter blanks as delivered by the feeding and skiving rolls 12 and 14.

At its right hand end the shaft 34 carries a pinion 39 and this remains in mesh at all times with the pinion 23 on the tubular shaft 22 already mentioned, that is, the swinging movement of the shaft 34 in the frame 35 is concentric with the axis of the shaft 20 and consequently with the gear 23 thereon. The shaft 34 is carried by bearing boxes 40 which are adjustable in the sides 15 of the frame 35 so that the shaft 34 may be moved bodily toward or from the shaft 20 and the pressure of engagement between the blades 33 and the anvil section 31 thus adjusted. The bearing boxes 40 are rigidly backed up by adjusting screws 41 threaded through ears upon the frame 35.

The pinion 23 on the tubular shaft 22 meshes with the elongated pinion 28 on the stub shaft 29 and the latter in turn is driven by the pinion 27 on the lower roll shaft 11. The provision of the elongated pinion 28 permits the longitudinal adjustment of the tubular shaft 22 with its pinion 23 without disturbing the driving connection of the parts. The clamping bolt 38 serves to hold the frame 35 in any position of longitudinal adjustment.

It will thus be seen that there is a direct geared driving train between the driving shaft 20 and the skiving rolls 12 and 14, and a more extended geared driving train between the shaft 20 and the slashing rolls 30 and 32. The skiving rolls 12 and 14 act as feeding rolls for advancing the successive counter blanks to the slashing rolls, supplementing the feed slide 18 in this respect, and having also in the illustrated machine, though not necessarily, a skiving function in addition. Disregarding the skiving function the machine comprises automatic feeding rolls for advancing successive counter blanks to continuously operating slashing rolls.

In operation the feed slide 18 is advanced to present a counter blank to the skiving rolls 12 and 14, the gauge 42 controlling the transverse position of the blank. The marginal edges 91 and 92 are skived as the blank passes the knife 17. The skived blank passes directly into the bite of the slashing rolls 30 and 32, whereupon the skived edge 92 is slashed by the cuts 93 and the slashed blank ejected from the machine ready for the clam shelling operation. If longer or shorter slashing cuts are desired the clamping bolt 38 may be loosened and the tubular shaft 32 with the frame 35 may be slipped longitudinally one way or the other and again clamped. If the slashing knives 33 fail to cut cleanly the adjusting screws 41 may be tightened and the cutting pressure increased. If it is desired to discontinue slashing the blanks the clamping bolt 38 may be removed and the frame 35 swung downwardly to the downwardly inclined position of Fig. 1 where it may remain out of the way in readiness for further use.

The slashing mechanism of my invention may be incorporated in any organization of counter machinery desired by the counter manufacturer. For example, frequently the counter blanks are passed directly from the skiving machine to clam-shelling rolls, and sometimes printing rolls are interposed in the feeding path so that the blanks 7

emerge from the machinery in skived, printed and curved or clam-shelled condition and are ready for presentation to the molding machine.

As suggested in Fig. 1 the slashing rolls 24-32 may be interposed in such a system in advance of the rolls for performing these supplementary operations. The rolls 50 and 51 are mounted in an auxiliary frame at some distance behind the slashing rolls and feeding mechanism comprising an endless band or apron 52 running between guide bars 53 is provided for picking up the slashed counter blanks as they leave the rolls 24-32 and conveying them one by one to the rolls 50-51. The action of these rolls is to curve the blanks into U-shaped contour or to clam shell them, as it is termed in the counter industry. The feeding apron may be of any convenient length, a broken away section being suggested in Fig. 1.

It will be understood that the counter blank shown in Fig. 3 is illustrative only and that the mechanism of my invention may be adapted for slashing counters of any desired shape or design by appropriate modification, all within the scope of the invention.

Having thus disclosed my invention, I claim as new and desire to secure by Letters Patent:—

1. A machine for operating upon counters, comprising skiving mechanism of the matrix type for skiving one edge of a counter blank, and slashing mechanism geared to said skiving mechanism and including a presser roll, a rotary blade carrier arranged to engage the skived blank as it passes from the skiving mechanism, and means for adjusting the location of the blade carrier with reference to the counter blank.

2. A machine for operating on counters, including counter-feeding rolls, a frame mounted to swing toward and from said rolls and also for adjusting movement in a direction parallel to the axes of said rolls, and slashing mechanism carried thereby.

3. A machine for operating on counters, including a drive shaft, matrix skiving rolls gear driven thereby, and slashing rolls gear driven from one of the skiving rolls independently of the drive shaft.

4. A machine for operating on counters, including cooperating matrix skiving rolls, and slashing rolls arranged to receive a counter blank passing from the skiving rolls and being axially adjustable with respect to the skiving rolls.

5. A machine for operating on counters, including a drive shaft, matrix skiving rolls driven thereby, an elongated pinion gear driven by one of said rolls, and slashing rolls gear driven by said elongated pinion, and adjustable axially with respect to the matrix rolls.

6. A machine for operating on counters, including an anvil roll and a cooperating blade-

carrying slashing roll geared thereto, and means for bodily moving one roll with respect to the other to predetermine their cutting pressure.

7. A machine for slashing a rocker-bottom counter, which includes cooperating feeding rolls, one having a ring of short axially disposed sharp-edge blades and the other a corresponding anvil ring of soft metal.

8. A machine for skiving and slashing a rocker-bottom counter, which consists in matrix skiving rolls, an anvil roll mounted in the rear of said skiving rolls, and a cooperating roll geared to the skiving rolls and having a ring of short axially disposed slashing blades thereon.

9. A counter slashing machine having a driving shaft, a frame pivotally mounted thereon, a tubular shaft concentric with the driving shaft and driven in the opposite direction therefrom, an anvil roll carried by said tubular shaft, a gear driven shaft journalled in the frame, and a slashing roll carried by said latter shaft.

10. A machine for operating on counters, comprising a reciprocating feed slide, feed rolls arranged to advance successive counter blanks presented thereto by said feed slide, and continuously operating rotary slashing rolls cooperative to receive blanks from the feed rolls and to slash them.

11. A machine for slashing rocker-bottom counter blanks, comprising a work table, gauge 30 and feed rolls for advancing successive blanks in flat condition along a predetermined path, in combination with a presser roll and a cooperating knife carrier having a series of straight spaced blades arranged to make slashing cuts of varying 35 length in the lower marginal part of blanks presented thereto.

12. A machine for operating on counters, having in combination, cooperating skiving rolls, cooperating clam shelling rolls, feeding mechanism 40 for conveying a skived counter blank from one set of rolls to the other, and means for slashing the blank in the course of its travel from one to the other.

13. A machine for operating on counters, having in combination, counter skiving mechanism, a roll equipped with slashing knives for slashing a skived counter blank delivered to it from said skiving mechanism, rolls for performing a secondary operation on a skived and slashed blank, 50 and feeding means for delivering successive blanks thereto.

14. A machine for operation on counters, including counter-feeding rolls and slashing mechanism including a plurality of short straight 55 blades spaced in parallel relation and adjustable longitudinally in a line transverse to the direction of feed, whereby the length of the slashes imparted to a counter may be varied.

CHARLES C. GILLIS. 60
